UNITED STATES PATENT OFFICE.

WILLIAM A. FREDERICK, OF BOSTON, MASSACHUSETTS.

CIRCUIT-CONTROLLING BUTTON.

1,307,856.

Specification of Letters Patent. Patented June 24, 1919.

Application filed February 7, 1918. Serial No. 215,741.

To all whom it may concern:

Be it known that I, WILLIAM A. FREDERICK, a citizen of the United States, and resident of Boston, in the county of Suffolk and State of Massachusetts, have invented certain new and useful Improvements in Circuit-Controlling Buttons, of which the following is a specification.

This invention relates to electric circuit controllers, and refers particularly to devices of this character employed in automobiles for signaling purposes such as the kind of electroresponsive devices known as electric horns. I do not limit myself however to this particular employment, as my improved device is useful for many other purposes.

The object of my invention is to provide a simple and inexpensive circuit controller which may be quickly secured in position for use by clamping it between a nut and whatever surface the nut is usually set against.

To this end, my invention consists in the device substantially as hereinafter described and claimed.

Of the accompanying drawings:

Figure 1 is a side elevation of my improved circuit-controlling button, mounted on the upper end of the steering post of an automobile.

Fig. 2 is an under plan view of the button removed from the steering post.

Fig. 3 represents a section on line 3—3 of Fig. 1, omitting the nut and post.

Fig. 4 represents a section on line 4—4 of Fig. 1, omitting the nut.

Fig. 5 is a detail view of the insulating ring and its conducting strips, removed from the cap or shell portion of the button, 40 said view showing the opposite side of the ring from that which appears in Fig. 4.

Similar reference characters designate similar parts in all of the views.

The cap or shell portion 12 is connected to 45 the thin flat foot 13 by a spring neck 14, these parts being preferably formed integrally of thin sheet metal such as steel. The foot 13 is adapted to be clamped between the top α of a steering post and the 50 nut γ which is employed to hold the steering wheel to the post. Said foot may be U-shaped, as shown in Fig. 2, to span the usual threaded top of the post, or may be in the form of a complete flat ring instead of U-shaped.

Mounted in the cap 12 is an insulating

ring 15. It may be fastened in place, but I find in practice that it is sufficient to have the ring fit the interior of the cap, with such friction as will enable it to be easily removed for inspection or cleaning or attaching or detaching the wires presently referred to.

The ring 15 carries two conducting strips 16, 17, each having ears at its ends overlapping the under surface of the ring and secured thereto as by rivets 18.

When two circuit wires 19, 20, are employed, one is suitably connected to an ear of strip 16 and the other to an ear of strip 17, as by clamping them under said ears. If but one wire is employed, it may be connected to the ears of both strips.

With the device constructed and mounted as indicated in Fig. 1, the nut γ not only 75 secures the device in position for use by clamping the foot piece 13 between its under surface and the top of steering post α , but it serves to complete the electric circuit when the cap 12 is depressed to cause the edges of the strips 16, 17, or their ears, to bear on the top of the nut. It is to be understood, of course, that normally the cap is held by the resilience of neck 14 sufficiently high to prevent completion of the circuit.

With the construction illustrated, both wires lead to the electroresponsive device, including, of course, a source of electricity such as a battery. As the particular device the circuit of which is to be controlled forms 90 no part of my invention, it is unnecessary to illustrate the same.

When my improved button is employed in connection with an electroresponsive device so mounted or carried that the post α , or whatever carries the nut γ , can be connected to "ground", such as the frame of an automobile, one of the wires 19, 20, may be omitted, the other wire being then connected to both of the strips 16, 17, if desired.

It will now be understood that the device is adapted to be applied, without change or alteration in its construction, to automobiles having either double or single wire connections. If two wires are employed, they are 105 connected to the two strips 16, 17, which are permanently spaced from each other so as to necessitate the interposition of the nut between them (resulting from depressing the cap) to complete the circuit, the nut being included in said circuit. On the other hand 110 it is only necessary to omit one of the wires

19 or 20 when the post or nut y is "grounded" as just described, for a single wire connection as just explained. The nut however, in this case also, is included in the circuit.

5 Whether one wire or two wires be employed, it or they will preferably pass through a slot or opening 21 in the spring neck 14.

Having now described my invention in 10 one of its embodiments, without attempting to explain all modifications thereof, or all of its possibilities of use, what I claim is:

1. The combination with a nut and a member supporting said nut, of a cap having an 15 integral foot piece adapted to be clamped between said nut and its support, said cap and foot piece having a resilient connecting neck, an insulating ring in said cap, and a

pair of contact strips for wire connections separately connected to said ring, said strips 20 being permanently laterally spaced whereby a circuit can be established only by the simultaneous contact of said strips with said nu:

2. A device of the character described, comprising a cap having an integral yielding connected foot piece, an insulating ring in said cap, a pair of contact strips for wire connections separately connected to said ring, and a bridging contact for said strips, said strips being permanently laterally spaced whereby a circuit can be established only by the operative interposition of said bridging contact between said strips. 30

In testimony whereof I have affixed my signature.

WILLIAM A. FREDERICK.
